DESIGN FOR A DISPLAY HOLDER OR SIMILAR ARTICLE

Adam P. Nielwocki, Irvington, N. J.

Application June 8, 1938, Serial No. 77,668

Term of patent 3½ years

To all whom it may concern:

Be it known that I, Adam P. Nielwocki, a citizen of the United States, residing at 51 Harrison Place, in the town of Irvington, county of Essex, and State of New Jersey, have invented a new, original, and ornamental Design for a Display Holder or Similar Article, of which the following is a specification, reference being had to the accompanying drawing, forming part thereof.

Fig. 1 is a perspective view of a display holder or similar article embodying my invention.

Fig. 2 is a top plan view thereof, and

Fig. 3 is an end elevational view, and

Fig. 4 is an underplan view thereof.

I claim:

The ornamental design for a display holder or similar article, as shown.

ADAM P. NIELWOCKI.
